UNITED STATES PATENT OFFICE.

ROBERT M. OVERALL, OF BROOKLYN, NEW YORK.

CONTROLLING DEVICE FOR PRINTING APPARATUS.

Application filed April 2, 1926. Serial No. 99,362.

This invention relates to improvements in controlling devices; especially controlling devices for printing apparatus.

An object of this invention is to provide a controlling device by which characters arranged in a certain order can be printed in a totally different order or succession, without alteration of their arrangement in the printing apparatus which enables impressions of such characters to be obtained.

A further object of the invention is to provide a controlling device for printing mechanism in the form of a convenient and effective attachment for said mechanism capable of being utilized whenever required without change of structure of the printing mechanism, or even readjustment of the latter; so that when the controlling device is not in actual use, the printing apparatus can be employed in the regular and usual way.

Another object of the invention is to provide a controlling device for printing mechanism of such construction as to be easy to handle and certain in operation, and still adapted to permit the printing apparatus to give a comparatively large output.

Still other objects and advantages of the invention are set forth in the following description, taken with the drawings; and the novel features are defined in the appended claims; but the disclosure is illustrative only, and I may vary the details of shape, size and disposition of parts, without exceeding the scope of the invention, as indicated by the broad and general meanings of the terms in which the appended claims are expressed.

On said drawings,

Figure 1 is a top plan of a controlling device according to my invention with the parts in starting position;

Figures 2 and 3 are opposite end views thereof seen from the left and right, respectively of Figure 1;

Figure 4 is a section of a detail on line 4-4 of Figure 1;

Figure 5 is a view similar to Figure 1, with the parts in mid-position;

Figure 6 is a section on the line 6-6 of Figure 1;

Figure 7 is a top plan of a detail;

Figure 8 is a section on line 8-8 of Figure 7;

Figure 9 is a section on the line 9-9 in Figure 5;

Figure 10 is a bottom plan of the part shown in Figure 9;

Figure 11 is a front view; and Figure 12 a top plan of the device with the parts in final position;

Figure 13 is an end view of the holder for the card or sheet to be printed, seen from the left thereof, as shown in Figure 12; and

Figure 14 is a section on the line 14-14 of Figure 12.

The same numerals identify the same parts throughout.

Referring to the particular construction shown in the drawings, I use the numeral 1 to indicate a base or support 1, which has the form of a flat plate of metal or any other suitable material. On the base is a carrier 2 in the form of a frame which bears a stencil or shield 3 in the form of a plate secured along one edge to one end of the frame beyond one side of the base 1; for example, the upper side or edge with reference to the position of the parts shown in Figures 1, 5 and 12. In practice, the operator's place will be adjacent the opposite edge of the base 1 to enable him to conveniently manipulate the carrier 2 and the other parts which the device comprises. The carrier moves from one end of the base 1 to the other, along a guide bar 4 and it carries with it not only the stencil 3, which is fixed to the carrier, but also a card holder 5 which is mounted in the carrier, so that it can be moved towards one side or the other of said carrier when this carrier is in its starting, middle or final position. The stencil plate has a slot 6 therein shown at 6, and an aperture or opening 7; the opening 6 being spaced from the opening 7. I also show at 8 in dotted lines, the position of a printing plate which will have characters thereon in the form of letters, words and figures, and these characters can be reproduced in a different arrangement on the surface of a card disposed in the holder 5 merely by exposing a part of these characters in succession through the openings 6 and 7. The printing plate 8 will be below the stencil 3 as shown in Figure 3, for instance, and between the stencil and the surface of the plate bearing the characters to be printed is a ribbon 9 similar to the ribbon of a typewriter so that when the card or sheet to be printed is pressed so as to force part of its surface against part of the surface of the ribbon which is exposed through

the opening 6 or 7, and that part of the ribbon against the characters on the plate 8, the desired effect on the surface of the card will be obtained. To this end, I may make use of 5 a pressure roller 10 mounted upon a shaft 11, as indicated in broken lines in Figures 2 and 3. This roller may be so controlled that it is depressed as required, and caused to act upon the card, so that the card makes 10 contact with the portion of the ribbon exposed through the openings 6 or 7, according as either of these openings may be utilized. The printing plate 8 will, of course, be mounted in fixed position on a suitable 15 support, and the roller 10 may be held and operated by means of any suitable mechanism to cause it to rise and fall, likewise to move back and forth if desired to a certain extent to pass over the full width of the 20 openings 6 and 7. Machines which work with such plates 8 and ribbons 9 and contain pressure rollers 10, are in common use, and some of them are designated by the 25 term addressographs. They are employed for various purposes, such as the printing of index cards, etc., and need not be further described here, as my invention relates simply to a controlling device to be used with such a machine by securing it to the flat 30 top or frame-work thereof in position to co-operate with the plate 8 and ribbon 9, and enable the roller 10 forming a part of such machine to be employed in the ordinary way.

The carrier 2 has the form shown in Figures 1, 5 and 12, for example, and is approximately U-shaped, the ends of the arms thereof terminating in bearings 12 through which the bar 4 passes, so that the carrier can slide easily along this bar. Adjacent the opposite edge of the base 1, it is provided with rollers 13 to support it above the surface of the base, and enable it to move easily from one end thereof to the other. Starting at the left, with reference to Figure 1, the 40 movement of the carrier 2 with the stencil 3 and card holder 5 will be in a straight line until nearly the opposite end of the base is reached. Then, as will be more fully described later, a slight lateral movement takes place also before the movement longitudinally of the base 1 is finished. For this purpose, the bar 4 is mounted, so that it can swing to the required extent away from the adjacent edge of the base 1. It is, therefore, mounted in bearings at the upper ends 50 of links 14, journaled upon a bar 15 below the bar 4 supported in bearings 16 rigid with the base 1. Hence, when a force is exerted sidewise of the bar 4, it can swing 55 outward away from the adjacent edge of the base 1 to a certain extent and draw the carrier 2 with the stencil 3 and card holder 5 with it.

Adjacent the end of the base from which 60 the carrier starts is a diagonal slot in the

base 1 which receives an adjustable gauge or stop 18 which can be secured at various positions in the slot. On the top of the base adjacent the slot is a calibrated scale indicated at 19, to indicate the positions which the stop 18 is to assume under various conditions. This stop marks the limit for the carrier 2 at one end of the base 1, and its movement at the other end is terminated by a stop 20 in the form of an adjustable screw 70 in a bearing 21, which can be held in position by a lock nut 22. One side of the carrier has a projection 23 to enable the operator to seize it between thumb and finger, and move the carrier towards the stop 18. 75 The carrier is actuated to travel towards the stop 20 by means of a spring 24 in the bar 4, the latter being hollow to receive this spring. One end of the spring is secured inside the bar 4, and the other end is attached to a pin 25 in the bar 4 but fixed to one of the bearings 12, preferably, the bearing beneath the projection 23. As indicated in Figure 4, this bearing may have a projection 26 extending through a slot 27 80 in the bottom of the bar or guide 4, and to this projection 26, the pin 25 may be secured in any suitable way. Hence, when the carrier is not held against movement, the spring 24 will act to draw it to the right until it 85 encounters the stop 20.

I shall now describe the construction of the card holder 5 which is movably mounted in the carrier 2. This card holder comprises a plate 28 along the sides of which are upturned flanges 29. The plate 28 extends from the stencil 3 across the base almost as far as the bar 4, and at its corners adjacent the bar 4 it has upturned perforated lugs forming bearings 30 on the sides of the carrier 2 in line with these bearings 30 are lugs 31 which are perforated to receive the ends of a guide-bar 32 passing through the bearings 30, and the holder 5 can thus slide in one direction or another, along the bar 32. 90 A binding screw 33 mounted in one of the lugs 31 engages the bar 32, and holds it against displacement. The bearing 30 at the right in Figures 5 and 12, is shown as provided with a projection 34, similar to the 95 projection 23, to enable the operator to seize the card holder and move it. Abutting the opposite bearing 30 is a spring 35 coiled around the guide-bar 32 and attached to this bar at its opposite end by means of an 100 anchoring screw 36. This spring tends to 105 impel the card holder towards the side of the frame at which is located the projection 23.

Rigid with one of the flanges 29 at the 110 right of the card holder 5 is a guide projection 37 which slides through a bearing opening 38 in one side of the carrier 2. The card holder also carries a movable arm 115 or pressure member 39 which can be raised 120

and then moved down on top of a card or sheet of material to be printed, placed in the holder, to secure this spring or sheet in operative position. This arm 39 is mounted upon a pivot 40, the arm being movable up and down about this pivot, and this pivot 40 is secured to a swivel 41, engaging a bearing in a projection 42, which is part of the thickened edge 43 of the plate 28 beneath the guide bar 32. The portion of the plate 28 adjacent the guide-bar 32 is more elevated than the remainder of the plate 28, as indicated at 44, and beneath this raised portion 44 is a transverse connecting bar 45 which joins the two sides of the carrier 2. Resting upon this portion 44 is the flange 46 of a plate 47 which is disposed between the flanges 29 on top of the plate 28, this plate 47 having two openings 48 therein, and being shouldered at 49. Thus a card of some width can be placed in the holder 5, one edge abutting the shoulder 49, and the other edge lying upon the stencil 3. A similar shoulder may extend across the card holder joining the principal part of the plate 28 to the portion 44. The extension 46 has slots 50 therein, and the holder 5 carries threaded studs 51 which pass through these slots and bear binding nuts 52. By loosening these binding nuts, the plate 47 can be moved towards or from the stencil 3 and fastened in position by the nuts 52. The edge of the plate 47 adjacent the stencil 3 provides a shoulder 53 so that if a card or strip of relatively narrow width is to be printed, it is laid in the holder 5 with one edge abutting the shoulder 53, and the other edge over the stencil 3, and the arm 39 will serve as before to clamp this strip in place. The swivel 41 permits the arm to be swung from side to side as this swivel can be rotated in the holder 5; while the pivot pin 41 permits the arm to be lowered and lifted. A spring may be employed in connection with the pivot pin 41 to move the arm 39 downward and keep it pressed upon the card or the like, in the holder 5.

The left side of the carrier 2 is provided with a slot 54, through which projects a stop 55 attached to the adjustable gauge or stop 18. This stop is in the form of a pin which passes through a bore in the stop 18, and it can be adajusted and held in adjusted position by means of a binding screw 56, and when secured in place, this stop 55 marks the limit of the movement of the holder 5 to the left on the base 1. The stop or gauge 18 has a pointed or index projection 57 to enable it to be accurately located with respect to the marks on the scale 19, and it is made up of two members 58 and 59, one above the base and one below it, each of these members having guide projections 60 which enter the slot 17. Through the two members 58 and 59 extends a hole 61, the hole in the bottom member 59 being threaded, and a headed binding screw 62 secures the two members together. When one desires to move this gauge in the slot 17, the screw is loosened to enable the members to slide in the slot and then tightened to hold it at the point desired. Further, this gauge 18 carries a pivoted catch 63 mounted on a pin 64. The catch 63 is in the form of a bell crank lever, one end of which extends into an aperture 65 in the member 58, but loosely, so that the other arm of the catch which is horizontal can be raised. The end of this arm has a shoulder 66 thereon, to serve as a hook, and a projection 67 for the finger of the operator to raise this catch. Ordinarily, the catch will drop by its own weight to hold the carrier 2 in a position shown in Figure 5 by the shoulder 66 engaging the top edge of the side of the carrier 2. But when this catch is lifted by the operator pressing with his thumb on the projection 67, the carrier is liberated, as the catch then clears the edge 68 of the carrier 2. To check the holder 5 at a predetermined point when it moves with the carrier 2 as far as the catch 63 permits, the latter is mounted below the base 1, a movable stop which projects through an opening 69, a slight distance above the top surface of the base 1. The end of the catch which so projects is indicated at 70 and this end is the upturned extremity of a bar 71 disposed beneath the base 1 and attached by screws 72 to an arm 73, pivoted on a pin 74, mounted in bearings or lugs 75. This catch is best shown in Figure 7. Encircling the pivot 74 is a spring 76 which engages the down-turned front edge of the base 1 and the lower face of the arm 73, so as to urge this arm upward and make the end 70 project through the opening 69. Carried by the arm or lever 73 is a pair of perforated bearings 77, similar to the bearings 75, and mounting a similar pin or journal 74 on which rotates a roller 78. The screws 72 pass through slots 79 in the bar 71 and engage threaded holes in the arm 73, so that by the loosening of the screws, the slots 79 permit the longitudinal adjustment of the bar 71. The base 1 has slots 80 which expose the slots 79, so that the heads of the screws can be disposed in these slots below the level of the top surface of the base 1. As indicated in Figure 6, the roller 78 projects above the top of the base 1 through an opening 81, and when this roller is depressed as indicated in Figure 11, the catch comprising the upturned end 70 of the bar 71 is depressed, so as to withdraw the stop 70 from the opening 69 and then permit the holder 5 to move farther to the right when the carrier is urged to its final position.

On the top surface of the base 1 just beyond the aperture 81 towards the right of the base, I affix a cam piece 82 having an

incline or diagonally extending edge 83. This piece is secured to the top of the base 1 by fastening means such as screws 84. The adjacent side of the carrier 2 has on its lower face a projection 85, in line with the cross-bar 45, and when this carrier has traveled far enough to the right to cause the projection 85 to engage the diagonally extending edge 83 of the piece 82, a transverse movement 10 of the carrier swinging the guide 4 outward on the links 14 must occur. To give clearance for the piece 82, the adjacent side of the carrier 2 between the cross-bar 45 and the roller 13 on that side, is a little distance 15 above the base 1, as indicated in Figure 3. The purpose of this transverse movement will be described later.

As indicated by the numeral 86, the bar 45 is not straight but has a bend therein adjacent 20 the side engaged by the catch 63. On the lower face of this bar is a downward extending rib indicated at 87 running along the edge which is presented towards the stencil plate 3, and between the bend 86 and 25 the right end of this bar, this rib has a diagonal surface or section 88. When the carrier moves, this rib 87 runs in contact with a roller 89 mounted on a pivot bolt 90 which holds it in horizontal position on the 30 upper face of the base 1. As indicated in Figures 7 and 8, the pivot bolt 90 passes through the base and screw threads into a link 91 below the base pivotally held in place by a rivet 92. This link can be moved from 35 side to side to adjust the roller towards and from the rib 87. A binding screw 93 passes through a slot 94 in the base 1, and screw threads into the opposite end of the link 91. Hence, by tightening this binding screw, the 40 link can be locked in the desired position. A similar slot 94 through which the pivot bolt 90 passes allows movement of this bolt and the roller 89 when the link and roller are to be adjusted. The roller 89 by engaging 45 the rib 87 prevents movement of the carrier, the holder 5 and the stencil 3 by swinging the guide 4 outward on the links 14 until the cam piece engages the projection 85. The roller 89 is so mounted that this roller 50 simultaneously reaches the diagonal surface or portion 88 of the rib 87, and this roller then does not hinder the sidewise movement of the frame, but cooperates with the cam edge 83.

As stated above, the flanges 29 do not extend entirely along the sides of the card holder 5, but terminate adjacent the shoulder which runs along the edge of the raised portion 44. On the top of this portion adjacent 55 the swivel 40, I secure by a hinge, a member 95. The hinge for this member is shown at 96, and it may comprise a spring 97 to press down upon the member 95, and hold it flat against the top of the part 44 of the card holder. At its free end, the mem-

ber 95 has a down-turned end 98 which depends far enough to be in line with the end of the stop 55 when the gauge 18 is moved far enough along the slot 17 to bring the stop 55 into position to strike the down-turned end 98 of this member. When the holder 5 is pushed to the left as far as it will go in the carrier 2, the end 98 of the member 95 clears the side of the cross-bar 45, and drops as low as the top of the plate 48; but as soon as the holder moves in the carrier, far enough to bring the down-turned end 98 of the member 95 into engagement with the bend 86, the top of the bar 45 at this bend will lift the member 95. For this purpose, the upper surface of the bar 45 at the bend 86 may be rounded to enable it to have the desired effect on the member 95. The rib 87 follows the contour of the bend 86 and when the rib at the bend comes into engagement with the roller 89, the carrier does not move any further to the right, but then occupies its final position as Figure 12 shows, with the carrier abutting the stop 50 screw 20.

I may arrange in one of the links 44, a stop screw 99 which abuts the down-turned front edge 100 of the base 1, to limit the swinging movement of the guide 4 towards the base, and I may also recess the 55 base in the middle along the edge adjacent the stencil 3 as indicated by the numeral 101 directly adjacent the printing plate 8.

In operation, suppose it be desired to print the matter which appears upon the upper 100 face of the plate 8 below the stencil 3, but to change the order or succession in which the parts of such matter appear. Let it first be assumed that certain words or characters are on the upper face of the plate 8, as indicated by the numerals I, II, and III, and that it is desired to reverse the order of Group I and Group II, and to print the words made up by the characters of Group III not under Groups I and II, but to one 105 side or in line with same. I proceed by first putting a card in the holder 5, clamping it in place by the arm 39. This card is shown in dot and dash lines and is indicated by the numeral 102. It is illustrated as extending from the shoulder 53 out over the openings 6 and 7. The operator then takes hold of the projection 23, and forces the carrier to the right until it strikes the gauge 18. The stencil 3 now moves with it, and so does 110 the card holder 5, until this holder abuts the stop 55. Now the stencil covers Group I, but exposes the characters making up the numbers, or words, or both, of Group II through the opening 6. Holding the device in this 115 position, the operator now causes the roller 10 to descend to press part of its surface against the card, so as to force the portion of the card over the opening 6 against the ribbon 9, and this ribbon against the printing 120 125 130

- plate 8. Group II is then forced to make an impression against the card 102. The next position is the position of the parts shown in Figure 5. This position is attained merely by releasing the carrier so that the spring 24 in the guide 4 pulls it to the right as far as the catch 63 permits. The operator now lays hold of the projection 34 and forces the card holder 5 to the right 10 against the stop 70. The stencil 3 now lies in such position that Group I is exposed; while Group II is covered up, and the card upon which Group II has been printed near the right end has been carried so far past the printing plate, that the impression of Group II on this card is in advance of Group I, but in line with it. Holding to the projection 34, the operator again makes the roller 11 descend and Group I is now made 15 to give an impression in its turn on the lower face of the card 102. The two impressions are in line with each other, along the top edge of the card, but are reversed with respect to the order of Group I and Group II on the plate 8. When the card is taken out and turned over, the right edge in Figures 1 and 5 then becomes the left edge, and the matter printed upon it is of course read from left to right in the usual way. If, for 20 example, Group I on the printing plate reads Joseph and Group II should read Bowles, 70B 800, the order in which these words and numbers would appear on the card after printing is Bowles 70B 800 Joseph.
- 35 To complete the operation and obtain an impression of the characters making up the words or numbers or both of Group III on the printing plate 8, the parts are caused to assume the positions indicated in Figures 11 and 12. For this purpose the operator presses his thumb against the projection 67 to lift the catch 63. Spring 24 then actuates the carrier 2 to move a little bit farther. Before lifting the catch 63, the projection 34 is released, so that the holder 5 is not held 40 against the stop 70 when the spring 35 can force the holder 5 to the left a little. The carrier then travels far enough to engage and depress the portion of the roller 78 projecting through the opening 81, so as to remove the stop 70 from the path of the holder 5. Next, the projection 85 strikes the cam edge 83 and the carrier with the plate 3 and holder 5 moves laterally, the guide 4 swinging outward as above stated. This movement brings the card 102 in such position that the impressions which it has received from Groups I and II are now to the right of the plate 8, and have cleared same, and 45 opening 7 of the plate 3 has come into position to expose Group III which heretofore in the positions of the parts shown in Figures 1 and 5 have been entirely covered by the stencil 3. At the same time, the movement of the parts transverse of the base have drawn the card 102 with them, so as to bring the impressions received from Groups I and II in lateral alinement with the top row of characters of Group III. As shown, the opening 7 is somewhat larger than the opening 6, and upon roller 10 again being depressed, an impression is obtained from Group III on the card and this impression is not below the impressions of Groups I and II, but on the same line unless, of course, 50 the words or numbers, or both, formed by the characters of Group III take up more than one line. The order of the parts of Group III is not changed, but the position of this whole group with respect to Groups I and II is changed. The characters of Group III may set forth the address, occupation, and other facts concerning the person whose name is being indexed.
- The recess 101 is provided for the convenient removal of the printing plate 8 which in machines of the type for which my invention is designed, is displaced by moving it forward out of the machine in the direction of the guide 4.
- The gauge 18 and slot 17 are provided so that the position of the parts adjacent the left of the base 1 can be accurately obtained according to the number of characters in Group I which is to be covered when the stencil first exposes Group II through the opening 6. If Group I presents the first name of a person of say eight characters, the index projection 57 of the gauge and stop 18 should preferably be opposite the 55 numeral 8 on the scale and for long names, meaning that Group I contains more characters, the gauge is simply moved along the slot opposite the higher numbers of the scale. Where the gauge is adjacent the lower numbers, the stop 55 would not strike the adjacent flange 29 of the holder 5, because this flange does not extend far enough towards the cross-bar 45. Hence, I provide the member 95 with the down-turned end 98 to abut 60 against this stop when the conditions of work are such that the gauge must be located adjacent the lower numbers on the scale, for proper results.
- Having described my invention, what I believe to be new and desire to secure and protect by Letters Patent of the United States is:—
1. A controlling device for printing apparatus comprising an apertured stencil and parts comprising tension means to actuate the stencil successively into position to expose different characters in said apparatus part by part in succession.
  2. A controlling device for printing apparatus comprising an apertured holder for a sheet of material to be printed and a stencil, and parts comprising tension means for actuating both the holder and the stencil so that the stencil successively exposes groups

- of characters in said apparatus to be printed, and the sheet receives successive impressions from said groups.
3. A controlling device for printing apparatus comprising parts having sidewise movement for enabling characters in said apparatus to give impressions differing from the arrangement of said characters in said apparatus, said parts comprising tension means, and an adjustable gauge at one end of said movement for regulating the operation of said device.
4. A controlling device for printing apparatus comprising a stencil and parts having endwise movement to actuate the stencil successively into position to expose different characters in said apparatus part by part in succession, said parts comprising tension means in combination with an adjustable gauge to determine the initial position of the stencil, at the beginning of said movement.
5. A controlling device for printing apparatus comprising a holder for a sheet of material to be printed and a stencil having sidewise movement, and parts for actuating both the holder and the stencil so that the stencil successively exposes groups of characters in said apparatus to be printed, and the sheet receives successive impressions from said groups, said parts comprising tension means, in combination with an adjustable gauge to determine the initial position of the stencil and holder, at the beginning of said movement.
6. A controlling device for printing apparatus comprising a carrier, a guide for said carrier along which the carrier is moved, and an automatically actuated part including a cam to move said guide and influence the movement of said carrier, when the carrier reaches a given point.
7. A controlling device for printing apparatus comprising a stencil with openings therein, and parts comprising tension means and a cam for moving the stencil in the direction of the length of said openings and crosswise thereof.
8. A controlling device for printing apparatus comprising a base, a carrier on the base, and movable along same, the base having a slot extending diagonally across the base adjacent one end, and an adjustable stop mounted in said slot to determine the starting position of the carrier.
9. A controlling device for printing apparatus comprising a movable carrier, a guide engaged by said carrier, rollers for supporting said carrier, and a cam member to engage the carrier and actuate it in a direction transverse of said guide.
10. A controlling device for printing apparatus, comprising a carrier, a guide-bar along which said carrier moves and links on which the guide-bar is mounted, to permit sidewise movement of the guide and carrier.
11. A controlling device for printing apparatus comprising a carrier, a guide-bar therefor mounted for transverse movement, and a cam element to engage the carrier as it moves along the guide and impart crosswise movement to the guide and carrier.
12. A controlling device for printing apparatus comprising a carrier, a holder movably mounted in said carrier, a base and a depressible stop mounted on the base to engage the holder.
13. A controlling device for printing apparatus comprising a carrier, a holder in the carrier and movably mounted therein, a base, a depressible stop mounted on the base to engage the carrier, and a roller associated with the stop and projecting through the base to be actuated by the carrier and move the stop out of position to engage the holder.
14. In a controlling device for printing apparatus, a stop comprising a pair of superimposed members arranged face to face, a screw for securing said members together, and registering projections on the opposing faces of said members forming a diagonal guide rib between them.
15. A controlling device for printing apparatus comprising a base, a stop on the base, and a pivoted releasing catch mounted on said stop.
16. A controlling device for printing apparatus comprising a holder, a pressure member to retain an article in said holder and an adjustable plate on said holder to vary the working width of same, the plate being movable towards and from the front edge of the holder.
17. A controlling device for printing apparatus comprising a holder consisting of a body formed of a sheet of metal, flanges at the sides of said body, said flanges being of less extent than the length of said sides, and a pivoted member adjacent one side of said holder to increase the length of one of said flanges.
18. A controlling device for printing apparatus comprising a carrier in the form of a frame having a cross-bar, the cross-bar being formed to provide a shoulder, a holder in said carrier, and a pivoted member secured to the holder and having one end bent down to engage the shoulder of the bar, and be raised thereby.
19. A controlling device for printing apparatus comprising a carrier, a guide along which the carrier moves, the guide having a slot therein, a bearing on the carrier engaging the guide, a spring in the guide, and a projection on said bearing passing through said slot into the guide and affixed to said spring.
20. A controlling device for printing apparatus comprising a carrier, a cross-bar in the carrier, a rib carried by the cross-bar, a

base, and a roller on the base in contact with said rib.

21. A controlling device for printing apparatus comprising a carrier, a base along 5 which said carrier moves, a cross-bar in the carrier, a rib on the cross-bar having a cam surface, and a roller on the base to engage said rib.

22. A controlling device for printing apparatus comprising a base, a guide roller on 10 the base, and an adjustable link on said base, pivotally supporting said roller.

23. A controlling device for printing apparatus comprising a base, a diagonally extending 15 transverse groove in said base, a gauge in said groove, and a scale on the base adjacent the groove.

24. A controlling device for printing apparatus comprising a base, a carrier movable 20 along the base, a bearing at one end of said base, and a stop screw in said bearing with a nut to hold the stop screw in adjusted position.

25. A controlling device for printing apparatus comprising a movable carrier, a 25 guide along which the carrier can be moved,

the guide being supported so that it can be actuated transversely, and a cam member to engage the carrier and impart transverse movement to said guide and carrier. 30

26. A controlling device for printing apparatus containing characters to be reproduced, a holder for material to receive impressions according to said characters, and means for changing the relative locations of 35 said characters and said material in such wise that a line of said characters will be reproduced on said material with parts of said line in reversed position.

27. A controlling device for printing apparatus containing characters to be reproduced, a shield associated therewith, and means for moving said shield to expose part 40 of a line of said characters while covering the remaining part and then to expose the 45 remaining part only, and a sheet of material movable with the shield to receive impressions of said parts in line with each other but reversed.

In testimony whereof I affix my signature.

ROBERT M. OVERALL.
